Patented Nov. 11, 1913.

UNITED STATES PATENT OFFICE.

EUGENE C. PFLEIDER, OF WEST ORANGE, NEW JERSEY.

MOTOR-CYCLE ENGINE-SUPPORT.

1,078,308.

Specification of Letters Patent.

Patented Nov. 11, 1913.

Application filed March 19, 1912. Serial No. 684,774.

To all whom it may concern:

Be it known that I, EUGENE C. PFLEIDER, a citizen of the United States, residing at West Orange, in the county of Essex and 5 State of New Jersey, have invented new and useful Improvements in Motor-Cycle Engine-Supports, of which the following is a specification.

This invention relates to motorcycles and 10 particularly to the mounting of the engine or motor in or upon the frame of the motorcycle, the object of the invention being to mount the motor in the machine frame in such a manner that it may be rocked or 15 swung to one side or the other of the machine frame for giving access to the working parts of the engine, thereby greatly facilitating the work of repair and adjustment and saving a great amount of time and annoy- 20 ance.

Manufacturers of motorcycles, as a general rule, limit the width of the tanks for supplying the oil, lubricant, etc., so as to provide a certain amount of accessibility 25 to the valves of the engine should they break or need replacement. With the swiveled suspension hereinafter described, a tank may be made of any suitable width without interfering with accessibility to the working 30 parts of the engine.

It is frequently necessary to grind the valves of an engine, requiring a special form of implement or screw driver which may be used for the purpose. With the present 35 improvement, in view of the fact that the engine may be swung to one side or the other, any ordinary screw-driver may be employed for the purpose or other implement which may be readily carried in the 40 tool bag on the machine.

Should the replacement of the valves be necessary on the road, this may be accomplished without the removal of the engine from the frame.

45 In most air cooled engines, such as are used on motorcycles, the employment of heavy lubricating oil results in the deposits of carbon in large quantities on the head of the cylinder and the valves and under the 50 present mounting of these engines, it is necessary to move the entire motor from the machine to remove the carbon. As this is necessary for about every five hundred miles of travel of the machine, the work of clean- 55 ing out the carbon becomes very arduous and

annoying. By means of the present invention all these parts may be readily gotten at by a simple operation which will require only a few minutes. It is also feasible to replace a broken piston ring in a very short 60 space of time and should it be necessary to remove the motor from the machine this can be accomplished in a very small part of the time heretofore required. In fact, the 65 operation of renewing and repairing the working parts of the engine is so facilitated by this invention that there is no tendency for the operator to continue using the machine when the motor is badly carbonized or when one of the piston rings has become 70 broken and is, therefore, liable to score the cylinder.

With the above and other objects in view, the invention consists in the construction, combination and arrangement of parts, set 75 forth in and falling within the scope of the appended claims.

In the accompanying drawings:—Figure 1 is a side elevation, partly in section, of a sufficient portion of a motorcycle to illustrate the application of the present invention thereto. Fig. 2 is an end view of the same, showing by dotted lines the manner of rocking or tilting the engine to one side. Fig. 3 is a detail vertical cross section through one 85 of the trunnions and trunnion seats. Fig. 4 is a detail vertical cross section, showing the means for locking the motor to the frame.

Referring to the drawings, 1 designates 90 the drop frame of the motorcycle having mounted therein a motor embodying the crank case and cylinder 3.

In carrying out the present invention, trunnion blocks 4 are mounted at opposite places 95 and are designed to receive trunnions 5 projecting from the crank case 2 at diametrically opposite places, as shown in Fig. 1.

Each trunnion block 4 is provided with a substantially U-shaped seat 6 for the adjacent trunnion 5, said seat being open at the top, as best illustrated in Fig. 3 to admit of the ready insertion and removal of the trunnion.

7 designates a threaded bolt which passes 105 through the trunnion block and the frame 1, the inner extremity thereof being received in a threaded opening 8 in the adjacent trunnion 5. The bolt 7 is provided at its outer end with a squared head 9 adapting 110

it to be turned by means of a wrench or pliers and when adjusted to its proper position, this bolt 7 is held by means of a swing nut 10 either with or without a spring split washer 11 which prevents the nut 10 from turning off the bolt 7. The oppositely located bolts 7 may be removed or partially removed to admit of the removal of the trunnions 5 from the trunnion seats 6 in an upward direction. In view of the fact, however, that the trunnions rest in the seats on the blocks 4, there is no strain on the bolts 7 which merely serve, therefore, as retainers to prevent dislodgment of the motor under the conditions presented by road work.

In order to lock the motor, in its working position, the crank case is provided at the bottom with a pendent lug 12 which is internally threaded to receive a screw plug 13 having a projecting head 14 at its lower end which head forms a shoulder against which bears a flange of a union 15.

Extending around the bottom portion of the frame 1 is a fixed sleeve 16 projecting upward from which is a threaded stud 17 upon which the union 15 screws as shown in Fig. 4. When the parts are secured together, as shown in Fig. 4, the motor, as a whole, is held in fixed working position. In order to tilt the motor to one side or the other, it is only necessary to unscrew the union 15 after which, by uncoupling the muffle pipe and control rods or wires, the motor is free to be swung to one side for the purposes of adjustment or replacement of any parts. The motor may be entirely removed by withdrawing the inner ends of the bolts 7 from engagement with the trunnions 5. After all the parts directly connected with the motor have been detached, the motor may be lifted easily out of the frame as it is then only supported by the trunnion blocks. The motor may be re-

stored to its operative position in the same manner.

I claim:—

1. In a motor cycle, the combination with the machine frame, of a motor provided with trunnions, trunnion seats on said frame having an open side to admit the trunnions, bolts on the frame movable into and out of engagement with the trunnions, and means for locking the motor in fixed relation to the frame. 55

2. In a motor cycle, the combination with the machine frame, of a motor provided with trunnions, trunnion seats on said frame having open sides to admit the trunnions, bolts on the frame movable into and out of engagement with the trunnions, and a threaded union for locking the motor in fixed relation to the frame. 60

3. In a motor cycle, the combination with the machine frame, of a motor provided with trunnions, trunnion seats on said frame having open sides to admit the trunnions, and means for locking the motor to the frame embodying a rotatable union and a threaded extension adapted to be engaged by said union and forming a direct connection between the motor and the motor cycle frame. 65

4. In a motorcycle, the combination with the machine frame and motor, of trunnions on one of said elements, trunnion seats open at one side on the other element permitting the motor to be swung on a fore and aft axis without removal from the machine frame, and means for retaining the trunnions in their seats and releasing the same to admit of the removal of the motor from the frame. 75 80

In testimony whereof I affix my signature in presence of two witnesses.

EUGENE C. PFLEIDER.
